UNITED STATES PATENT OFFICE.

CHRISTOPHER STEWART ROBERTSON, OF JACKSONVILLE, FLORIDA.

SIDE WINDOW ATTACHMENT FOR AUTOMOBILES.

Application filed February 14, 1923. Serial No. 618,953.

To all whom it may concern:

Be it known that I, CHRISTOPHER S. ROBERTSON, a citizen of the United States, residing at Jacksonville, in the county of 5 Duval and State of Florida, have invented a new and useful Side Window Attachment for Automobiles, of which the following is a specification.

This invention relates to a side window attachment for automobiles, one of the objects 10 of the invention being to provide window frames mounted in a novel manner upon the sides of the automobile body and so connected to the doors that the window frames 15 will swing therewith to open and closed positions.

Another object is to provide socket members in the body and in the doors to receive portions of the attachment, means being employed for automatically closing the socket 20 members when the attachment is removed.

Another object is to provide an attachment of this character the parts of which are held firmly in place so as not to rattle, 25 it being possible readily to place the parts in position and to remove them.

Another object is to provide removable window frames, which, when not in use, can be stored in the seats of the automobile or 30 at other convenient places.

Another object is to provide a side window attachment which when set up for use will not detract from the appearance of the vehicle and will constitute a practically air 35 tight closure for the vehicle.

With the foregoing and other objects in view, which will appear as the description proceeds, the invention consists of certain novel details of construction and combinations of parts which will be hereinafter more 40 fully described and pointed out in the claims, it being understood that changes may be made in the construction and arrangement of the parts without departing from the spirit of 45 the invention as claimed.

In the accompanying drawings the preferred form of the invention has been shown.

In said drawings,

Figure 1 is a side elevation of an automobile having the side window attachment applied thereto.

Figure 2 is a view partly in side elevation and partly in section of the structure shown in Figure 1.

Figure 3 is a section on line 3—3 Figure 1. 55 Figure 4 is a section on line 4—4 Figure 1.

Figure 5 is a section on line 5—5 Figure 1.

Figure 6 is a section on line 6—6 Figure 2, said figure being on an enlarged scale.

Figure 7 is a view partly in side elevation 60 and partly in section of one of the window frames and its connections, a part of the frame being broken away.

Figure 8 is a section on line 8—8 Figure 7.

Figure 9 is a section on line 9—9 Figure 7. 65

Figure 10 is a section on line 10—10 Figure 7.

Figure 11 is a section on line 11—11

Figure 1.

Figure 12 is a transverse section through a 70 portion of the back of one of the vehicle seats.

Figure 13 is a section through a portion 75 of one side of the body showing a filler strip.

Referring to the figures by characters of reference 14 designates the body of a vehicle provided with a top 15 of the usual construction, the front bow of the top being indicated at 16. In the structure shown two 80 doors 17 and 18 are provided at each side of the vehicle and the seats 19 are formed with hollow backs 20 each having a suitably located closure. In the present instance two 85 hinged closures 21 are provided at the top of each back and are adapted to swing together after which they can be fastened in any suitable manner as by means of a strap 22. A spring supported bottom strip 23 is located in each of the backs 20 and the 90 side walls of each back are preferably formed with spacing strips 24 dividing the interior of the back into separate frame receiving portions. The interior construction 95 of the backs of the seats has been illustrated in detail in Figures 2 and 12. It is to be understood that each seat back is to receive two window frames, the yieldingly supported strips 23 holding these frames pressed yieldingly against the tops 21 so 100 that they will not rattle.

For the purpose of holding the frames in positions at the sides of the body special front and intermediate posts are provided. The front posts 25 are preferably triangular so as to hold the wind shield 26 in an inclined position as shown in Figures 1 and 2. Each post 25 has an upwardly extending stud 27 such as commonly employed for holding front posts in place. Extending 105 rearwardly from the lower portion of each post 25 is a tongue 28 having a downwardly

extending tubular or socket member 29 seated within a recess 30 in the wall of the body 14. An opening 31 extends through the tongue 28 and communicates with the interior of the member 29. In this opening is slidably mounted a pin 32 constituting a closure therefor, there being a spring 33 bearing against the pin and against a screw plug 34 which closes the lower end of the member 29.

An ear 35 is extended rearwardly from the upper portion of the post 25 and has an opening 36 therein disposed in vertical alignment with the opening 31. That portion of the post between ear 35 and tongue 28 is recessed longitudinally as shown at 37, the recess being rounded transversely as clearly illustrated in Figure 9.

Formed within the upper edge of each side of the body 14 between the front and rear doors 17 and 18 is a dove-tailed groove 38 shown in Figure 6. This groove is designed to receive a dove-tail 39 formed at the lower end of a side post 40. The upper end of this post has a stud 41 detachably and adjustably fastened in the forked end 42 of an arm 43. This arm has a bowed end 44 constituting one member of a clamp, there being another bowed clamp member 45 bolted to the arm 43 as shown at 46. The two bowed portions 44 and 45 are adapted to straddle and clamp upon the sides of the front bow 16, thus to support the arm 43 so that it will extend inwardly horizontally from the side of the bow 16 and provide a firm support for the upper end of the post.

Formed within the upper edge of each door 17 and 18 is a recess 47 containing a socket member 48 having a longitudinal slot 49 in the top thereof. A closure block 50 is slidably mounted in the socket member 48 and is yieldingly supported by a spring 51. When this block is in its normal or raised position it closes the slot 49 and has its upper face flush with the upper edge of the door.

A window frame 52 is provided for each door, and the front end of each of these frames is enlarged and rounded as shown at 53 so as to fit snugly within the rounded groove 37 of its post. A stud 54 is extended downwardly from this end of the frame and a recess 55 is provided in the upper portion of said end so as to receive the ear 35. A pintle 56 is extended downwardly from the upper wall of the recess 55 and is in alignment with the stud or pintle 54. Extending downwardly from the frame 52 near its other end is a fin 57 adapted to extend through slot 49 and bear against the block 50.

Formed at the side of the body 14 in the base 40' of the post 40 is a recess or socket 58 and this socket is in line with an

apertured ear 59 formed on the upper portion of the post 40.

The two frames used at each side of the car are of the same construction and are adapted to be placed in position by lowering the pintles and fins so as to engage the posts, socket portions and doors respectively. The pintles on the front frames 52 will enter the openings 36 and 31, pintles 54 pushing the pins 32 downwardly while fins 57 will thrust the blocks 50 downwardly. These blocks will exert a constant upward pressure against the fins and thus hold the parts against rattling. The upper pintle of each rear frame will be lowered into the ear 59 on post 40 while the lower pintle of each rear frame will enter the socket 58 in the base of the vehicle post 40.

The fins 57 are shorter than the slots 49. Thus when the doors are swung open the fins will shift longitudinally within the slots to compensate for the variation due to the movement of the doors and their window frames about different centers.

For the purpose of sealing the car when the attachment is in place shield strips 59' are secured to the sides of the bow 16 and are extended inwardly therefrom, their inner edges being formed with depending flanges 60 adapted to be lapped by the upper edges of the front window frames 52.

The rear side curtains 61 are secured, at their front edges, about a metal plate 62 bent or offset longitudinally to provide a seat 63 for the rear edge of the adjacent window frame 52. This construction has been shown in detail in Figure 11. A fabric strip 64 can be attached to the inner side of the lower portion of each frame 52 and will extend between the frame and the surface on which it is mounted, thus to constitute a weather strip to prevent the admission of air or water between the frames and the doors.

When the frames are lifted from their positions the pins 32 and blocks 50 will promptly close the openings thereabove. The frames can be housed in the machine as heretofore described. If desired the side posts 40 can be removed and stored within the machine. In this event the dove-tailed grooves 38 can be closed with filler strips one of which has been shown in section at 65 in Figure 13.

What is claimed is:

1. The combination with an automobile body having a hinged door and a top, of a post detachably mounted between the top and the side of the body, there being a socket in the top of the door, a window frame hingedly connected to the post, a member depending from the frame and slidably within the socket when the door is opened or closed, said door and frame being movable about individual non-aligning axes, and

means in the socket for exerting a constant pressure against said member.

2. The combination with an automobile body including a door having a socket in its upper edge, and a vehicle top, of a post secured to the top and to the side of the body, a window frame, alining pintles extending downwardly therefrom, means on the post and in the side of the body for receiving the pintles, a member on the frame for extending downwardly into the socket of the door to provide a slidable connection between the door and frame, and means in the door for exerting a constant pressure against said member, said means automatically closing the socket when the frame is disengaged from the door.

3. The combination with a vehicle body having a hinged door provided with a socket in its upper edge, there being a groove in the upper edge of the side of the body, of a post detachably mounted in the groove, a vehicle top including a bow, an arm detachably con-

nected to the bow and to the post, a window frame, downwardly extending pintles engaging the upper and lower portions of the post to provide a hinged connection to the frame out of alinement with the hinge of the door, and means on the frame and projecting into the socket in the door for connecting the frame and door for simultaneous swinging movement.

4. The combination with a vehicle body including a hinged door, a top, and a post detachably connected to the side of the body and to the top, of a frame hingedly connected to the post, a slidable connection between the frame and the door, a side curtain, and an angular stiffening strip secured to the side curtain and providing a seat for the frame when the door is closed.

In testimony that I claim the foregoing as my own, I have hereto affixed my signature.

CHRISTOPHER STEWART ROBERTSON.
